UNITED STATES PATENT OFFICE.

JOSEF JACOBS, OF BUISDORF, AND AUGUST NEFGEN, OF SIEGBURG, NEAR COLOGNE,
GERMANY; SAID JACOBS ASSIGNOR TO SAID NEFGEN.

CUTTING DEVICE FOR PRINTING-MACHINES.

1,103,292.

Specification of Letters Patent. Patented July 14, 1914.

Application filed November 9, 1911. Serial No. 659,318.

To all whom it may concern:

Be it known that we, JOSEF JACOBS, a subject of the King of Prussia, and resident of Buisdorf, near Cologne-on-the-Rhine, Germany, and AUGUST NEFGEN, a subject of the King of Prussia, and resident of Siegburg, near Cologne, German Empire, have jointly invented a new and useful Cutting Device for Printing-Machines, of which the following is a specification.

This invention relates to rotary printing machines for printing on a strip or web of paper supplied from a supply roll of the type in which printing cylinders of different diameters may be employed, the impression cylinder being driven from the printing cylinder by friction and a rotatable cutter being provided, adapted to cut the printed web of paper transversely into sheets.

The object of the present invention is to provide improved simplified mechanism whereby, when the printing cylinder is exchanged, the length of sheet cut by the cutting mechanism will be varied to correspond to the size of the particular printing cylinder in use without necessitating any other variation than that of exchanging the printing cylinders.

In carrying out the invention the rotatable cutter is geared up to the printing cylinder in such a manner as to be driven therefrom at the same angular velocity as the printing cylinder. By this means it follows that when the printing cylinder is exchanged, say, for example, for a cylinder of larger diameter, the web of paper will be traversed at a greater speed and will consequently be fed past the rotary cutter at a greater speed. As the rotary cutter, however, rotates at the same angular velocity as before, it follows that the printed web of paper will be cut into sheets of a longer length and of a length corresponding to the circumferential dimensions of the printing cylinder inserted. Thus it will be readily seen that, by merely exchanging the printing cylinder, the length of the sheets cut is simultaneously and correspondingly varied.

The printed web is fed to the rotary cutter at the same surface speed as the printing cylinder by means of tension rollers driven from the impression cylinder, the tension rollers being rotated at a somewhat greater

surface speed than the printing cylinder to 55 allow for stretch in the paper.

If desired the sheets may thereafter be fed to any suitable type of printing machine in order to print on one or both sides of the sheets and said additional printing machine 60 may be driven from the printing roller of the first printing machine, so that both the printing machine and the cutting device are driven at the same speed. It will however be readily understood that the two 65 printing machines can only be combined when the cutting device is interposed.

In order that the invention may be more clearly understood, reference is made to the accompanying drawings which show by way 70 of example the preferred method of carrying out the invention, the figure illustrating the combination of two printing machines between which a cutting device is interposed.

a indicates the paper supply roll, from which the paper is guided over guide rollers *b* and *c* between the printing roller *d* and pressure roller *e* of a rotary printing machine. The paper is thereafter led over 75 guide rollers *f* and *g* to and between tension rollers *h*, *h'*, *h²*, *h³* and thence over a stationary table *i* which terminates at its delivery end in a knife edge adapted to coact with a knife *m* mounted upon a rotatable 80 shaft *v*.

The tension rollers *h* *h'* and *h²* *h³* may be of any known type such as that shown in the drawings. Mounted on the spindle of the tension rollers *h* is a gear wheel *w* over 85 which passes a chain *x* passing around a gear wheel *k* mounted on the shaft of the pressure roller *e*, and the tension rollers *h* and *h²* are geared together by means of a chain *o* passing around suitable chain wheels 90 mounted on the axles of the rollers *h* *h²*. The ratio of the gearing between the tension roller *h* and the pressure roller *e* is arranged so that the tension rollers rotate at a somewhat greater surface speed than the printing roller *d*. For example if the printing roller is adapted to print one meter length 95 of paper per unit of time, the gearing between the pressure roller *e* and tension roller *h* is so chosen, that the tension rollers 100 *h* *h²* rotate at a surface speed of 101 cm. per unit of time so as to constantly maintain the paper under tension.

The shaft v of the rotatable cutting knife m is driven by means of a gear wheel y thereon, gearing with the gear wheel z mounted on a shaft z' which carries a chain 5 wheel n driven by means of a chain o passing around a chain wheel p mounted upon the shaft of the printing roller d . The ratio of the gearing between the printing roller d and rotatable shaft v of the cutting knife m is such that the angular velocity of the cutting knife m is the same as that of the printing roller d so that the cutting knife m on co-acting at each rotation with the knife edge of the table i cuts the 10 paper strip into sheets of a length corresponding to the circumferential dimensions of the printing roller d . The cut sheets fall into any suitable form of endless conveyer q from whence they are taken by a gripper 15 r on the printing roller s of a second printing machine adapted to print on one or both sides of the sheets.

The driving chain wheel t of the second printing machine may be directly driven 20 from a chain wheel mounted on the shaft of the printing roller d of the first printing machine by means of a chain u . It will of course be readily understood that if desired the chain gearing may be substituted by 25 any other suitable form of driving mechanism.

We claim:—

1. In a rotary printing machine for printing on a web of paper supplied from a supply roll, the combination with an exchangeable printing cylinder and an impression cylinder frictionally driven the one from the other; of a rotary cutter for cutting the printed web into sheets of a length corresponding to the size of printing cylinder and means for driving the rotatable cutter from said printing cylinder at the same angular velocity as the printing cylinder, whereby, when the printing cylinder is exchanged, the length of sheet cut by said cutter will be automatically and correspondingly varied.

2. In a rotary printing machine for printing on a web of paper supplied from a supply roll, the combination with an exchangeable printing cylinder and an impression cylinder frictionally driven the one from the other; of a rotary cutter for cutting the printed web into sheets of a length corre-

sponding to the size of printing cylinder, means for driving the rotatable cutter from said printing cylinder at the same angular velocity as the printing cylinder, whereby, when the printing cylinder is exchanged and without necessitating any change in gearing, the length of sheet cut by said cutter will be automatically and correspondingly varied, tension rollers intermediate said cylinders and cutter and driving mechanism for rotating said tension rollers from said impression cylinder at a somewhat greater surface speed than the printing cylinder.

3. In a printing machine for printing on a web of paper supplied from a supply roll, the combination with a guide roller and a printing roller for printing one side of the paper, of tension rollers, a table over which the paper passes from the tension rollers, an endless conveyer, means coacting with the table for cutting the paper into sheets and delivering said sheets directly onto the conveyer, and a second printing roller onto which the sheet of paper is delivered from said conveyer for printing its other side.

4. In a rotary printing machine for printing on one side of a web of paper supplied from a supply roll, the combination with an exchangeable printing cylinder and an impression cylinder frictionally driven the one from the other; of a rotary cutter for cutting the printed web into sheets of a length corresponding to the size of printing cylinder, means for driving the rotatable cutter from said cylinders at the same angular velocity as the printing cylinder, whereby, when the printing cylinder is exchanged, the length of sheet cut by said cutter will be automatically and correspondingly varied, a conveyer to which the sheets are supplied, a second printing cylinder to which the sheets are delivered from said conveyer for printing the other side thereof, and mechanism for rotating said second printing cylinder from the first mentioned printing cylinder.

In witness whereof we have hereunto set our hand in the presence of two witnesses.

JOSEF JACOBS.
AUGUST NEFGEN.
